Patented July 15, 1919.

UNITED STATES PATENT OFFICE.

LINO SCUSA, OF PHOENIX, NEW YORK.

GAGE.

1,309,700.

Specification of Letters Patent. Patented July 15, 1919.

Application filed February 11, 1919. Serial No. 276,418.

To all whom it may concern:

Be it known that I, LINO SCUSA, a citizen of the United States, residing at Phoenix, in the county of Onondaga and State of New York, have invented certain new and useful Improvements in Gages, of which the following is a specification.

This invention relates to improvements in gages, designed for use by machinists, tool-makers, inspectors, and the like, and the invention relates particularly to snap or limit gages employed for gaging manufactured or stock articles, wherein the gages are adjusted and set and used for turning out a number of similar parts.

The object of the invention is to provide more positive, precise and quick-acting locking means for holding the gage-members in the various adjusted positions. A further object is to provide novel and simple means for insulating certain parts of the gage against the heat of the operator's hands.

A particular object is to improve the devices shown and described in my United States Patent No. 1,279,919, dated September 24, 1918.

The various features and parts of the invention will be understood from the detailed description which follows, and by reference to the accompanying drawing, in which—

Figure 1 is a side elevation of the complete device, a portion of one of the arms being cut away to show the construction, arrangement and operation of one of the gage members.

Fig. 2 is an end elevation of the same.

Fig. 3 is an enlarged broken section, taken on line 3—3 of Fig. 1; showing one of the gage members locked in the operation position.

Fig. 4 is an enlarged detail view of the gage member and the locking element.

Fig. 5 is a similar view; showing the eccentric locking part released and ready to be operated.

Figs. 6, 7 and 8 are respectively a bottom face view, a central vertical section, and an edge view of one of the insulating members.

In the drawing, 2 represents the body of the gage, which is preferably made of steel

or iron, in the form of a horseshoe, and comprises a thin flat web 3, which is reinforced at its inner edge by a semi-circular flange 4. Beyond the ends of the flange 4, the arms of the body are provided with corresponding cylindrical enlargements 5—5, and which are bored out, at 6, to receive similar reciprocable cylindrical gage members, 7—7' and 8—8', whose square-cut inner ends comprise the gage-points, which project into the bight of the body 2. The outer ends of said gage members are rounded, so as to reduce the frictional engagement of a series of adjusting screws 10, which are threaded into the outer ends of the holes 6. The screws 10 are employed for adjustably holding the corresponding gage members the required distance apart.

Each of the gage members is provided with oppositely facing plane bevel portions 11—11' extending longitudinally, for providing a portion V-shaped in cross section, as 11'' (see Figs. 3, 4 and 5), adapted to be engaged by a rotary locking part 12, the latter being journaled in a socket or hole 12', in the arm of the body 2, the said socket being disposed laterally and at right angles to the hole 6. The ends 12^a of the locker 12 are cylindrical and coaxial, and intermediate these ends is an annular groove 80 formed by two oppositely facing conical portions 12^b, which are joined together by a narrow neck 12^c. The conical portions 12^b have substantially the same angle and fairly engage the plane faces 11—11' of 85 the gage members when the locker is moved into the locking position. In order to accomplish the positive locking of the gage members, in a novel and simple manner, the axis of each pair of cones 12^b is arranged eccentric to the axis of the ends 12^a, as shown in Figs. 3 and 5. One end of each locker 12 has a screwdriver slot 12^d. Owing to the eccentricity of the cones 12^b, only a slight rotary movement, clock-wise, of the lockers 90 is required to bring the cones into tight frictional engagement with the planes 11—11', for locking the gage members against longitudinal movement.

Fig. 3 shows the parts in the fully locked 100

position, while Fig. 5 shows the locker in the released position. Each of the gage members 7-7' and 8-8' is provided with its own locker 12, and therefore each member may be adjusted and set independently of the others. The slotted ends of the lockers of each pair are reversed, as shown in Fig. 1. The object of this is to permit each locker to be turned clock-wise without disturbing the adjustment axially of the gage members as fixed by the screws 10. By providing the similar oppositely facing cones 12^b, which straddle the V-shaped portion 11'', the gage members are held from rotation, and at the same time the pressure exerted by the lockers is always at right angles to the axis of the lockers. Hence, if there is any looseness of the gage members in the holes 6, the corresponding members are forced and rigidly held against the corresponding sides of the holes 6 thereby maintaining the axial alinement of the member.

Where the gages are in constant use, the heat from the operators' hands frequently tends to expand the metal comprising the web 3 sufficiently to distort or render the gage inaccurate, to the extent, at least, of fractional thousandths of an inch. In some cases, where fine and exact gaging is required, this distortion of the arms of the gage is enough to cause the rejection of the work. To overcome this heating and distortion of the gages, I provide novel, simple and effective means for insulating the body 2, which consists of similar relatively thin sheet metal rosettes 15 and 15', which are preferably mounted on the opposite sides of the web 3, near its rounded end, and which are secured in place by screws 16, as shown in Figs. 1 and 2. The rosettes 15-15' are slightly cupped at their inner faces, and each is provided with three or more short feet 17, which alone engage the surfaces of the web 3, thereby providing several narrow openings 17', for the circulation of the air and the consequent cooling of the parts.

To set my improved gage, the operator first releases the lockers 12 by turning them to the left, for releasing the conical cams 12^b-12^c. He then rotates the adjusting screws 10 in the proper direction for permitting the corresponding gage members to be moved toward or away from each other. The gage members 7-7' are generally set for gaging the initial or rough cutting of the work, while the gage members 8-8' are set for gaging the finish of the work. The final adjustment of the gage members is accomplished by the operation of the adjusting screws 10, after which the lockers 12 are tightened up, as described.

My gage is extremely simple. The means for adjusting and locking the gage members

is novel, powerful and quick-acting. By the provision of the eccentric cones 12^b, I am able to effect the instantaneous locking of the gage members, and when the lockers 12 are properly made and hardened, it only requires an eccentricity of from five to ten thousandths of an inch to effect the rigid and positive locking of the parts. The provision of the eccentric cones 12^b obviates the necessity of employing the usual screw-threaded locking parts, thus insuring a longer life and the withstanding of rougher handling than any other gages of the class known to me.

Having thus described my invention, what I claim as new and desire to secure by Letters Patent, is—

1. A gage including a horseshoe-shaped body, a plurality of alining axially movable gage members supported by the arms of said body, each member having a portion V-shaped in cross section, and a locker rotatable in a plane at right angles to the axis of each gage member, the medial portion of each locker comprising two cones having a common axis which is eccentric to the axis of rotation of said locker and movable by turning the locker into frictional engagement with the V-shaped portion for locking the gage member in the adjusted positions.

2. In a limit gage, a body having spaced sockets, axially movable gage members each having longitudinal surfaces disposed in diverging plane in said sockets, and a cylindrical locker for each gage member, said lockers rotatable in perforations which communicate with said sockets, the medial portions of each locker comprising oppositely facing cones the axes of which are eccentric to the axes of said perforations adapted to frictionally engage the corresponding plane surfaces for locking the gage members against longitudinal movement.

3. In a gage, a horseshoe-shaped body, having transversely perforated arms, gage members arranged in pairs and movable axially in corresponding perforations, each gage member having a portion V-shaped in cross section, rotatable locking elements, said locking elements provided with conical portions whose axes are eccentric to the axes of rotation of said elements adapted to frictionally engage said V-shaped portion for locking said gage members from longitudinal movement during the gaging operations, and means for insulating said body from the heat of the operator's hands for preventing the distortion of said arms.

4. In a gage, a horseshoe-shaped body having transversely perforated arms, reciprocable gage members each having a longitudinally arranged portion V-shaped in cross section and one rounded end, an ad-

justing screw engaging the rounded end of each gage member, and a rotatable locker for each gage member, said locker disposed in a socket arranged at right angles to said gage member, the ends of said locker being cylindrical, and the intermediate portion of said locker comprising oppositely facing cones having an axis eccentric to the axis of said ends adapted to straddle and frictionally engage said V-shaped portion for locking and holding said gage member in the adjusted positions. 10

In testimony whereof I affix my signature.

LINO SCUSA.
